US00D843212S

(12) **United States Design Patent** (10) **Patent No.:** **US D843,212 S**
(45) **Date of Patent:** **** Mar. 19, 2019**

(54) **LID**

(71) Applicant: **YETI Coolers, LLC**, Austin, TX (US)

(72) Inventors: **Roy Joseph Seiders**, Austin, TX (US);
Matthew Joseph Petrillo, Austin, TX (US);
Steve Charles Nichols, Austin, TX (US)

(73) Assignee: **YETI Coolers, LLC**, Austin, TX (US)

(**) Term: **15 Years**

(21) Appl. No.: **29/596,970**

(22) Filed: **Mar. 13, 2017**

Related U.S. Application Data

(63) Continuation of application No. 29/544,227, filed on Oct. 30, 2015, now Pat. No. Des. 781,146.

(51) **LOC (11) Cl.** **09-07**

(52) **U.S. Cl.**

USPC **D9/443; D7/392.1**

(58) **Field of Classification Search**

(57) **CLAIM**

The ornamental design for a lid, as shown and described.

DESCRIPTION

FIG. 1 is a top, front, right perspective view of a lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are shown for the purposes of illustrating parts of the lid that form no part of the claim.

1 Claim, 4 Drawing Sheets
